TELEPHONE APPARATUS

Filed June 19, 1930

UNITED STATES PATENT OFFICE

JOSEPH O. CADIEUX, OF MERIDEN, CONNECTICUT, ASSIGNOR TO CONNECTICUT TELEPHONE & ELECTRIC CORPORATION, OF MERIDEN, CONNECTICUT, A CORPORATION OF DELAWARE

TELEPHONE APPARATUS

Application filed June 19, 1930. Serial No. 462,265.

My invention relates particularly to apparatus of the character set forth in my Patent #1,717,091.

One of the important advantages of that construction is the facility with which apparatus may be installed which installation includes the preliminary step of wiring and locating the wall plates with circuit terminals before the building is completed, the active parts of the apparatus being subsequently attached. On account of the fact that the wall plate or support is installed while the building is under construction, the terminals and contacts are likely to be covered with dirt and in fact the cable opening is quite large and admits dirt to the outlet box behind the wall plate. To avoid these difficulties I propose to provide a protecting housing adapted to be readily attached to the support to cover the conductor opening, the terminals and the contacts while plastering and other work is being completed. I have also sought to simplify and perfect the terminal and contact construction and the method of supporting and insulating the same.

Fig. 1 is a front view of a terminal wall plate with its wiring protector and showing an outlet box dotted.

Fig. 2 is a vertical sectional view.

Fig. 3 is a front view showing the circuit terminals without the protector.

Fig. 4 is a vertical section of a modification.

Figs. 5 and 6 are perspective views of devices for attaching the protector to the terminal sockets.

The wall plate 10 has an insulating block 11 attached to it by rivets 12.

This block 11 carries a series of terminal and contact members arranged in a row as shown in Fig. 3. Each unit consists of a terminal plate 14, jaw contacts 15 and 16 and one or more connecting feet 17 connected by rivet 18 to the terminal plate 14 and provided with a binding screw 19. The feet of the jaw contacts 15 and 16 are located in a groove in the rear of the block 11 and the jaws themselves pass forwardly through openings 20 arranged adjacent the respective binding screws. The plates 14 and screws 19 are also

preferably set into recesses 21 to assist in positioning them and also to assist in retaining the ends of the conductors 22. The plate 10 is preferably provided with an opening 23 extending along the upper edge of the block 11 and through which the various conductors are passed. The upper edge of the block 11 is provided with inclined portions 24 leading to the terminal plates so that the respective conductors are spaced apart by ribs 25.

A layer of insulating material 26 is also preferably provided interposed between the back of the block 11 and the face of the plate 10 to insulate the rear of the feet 17 from the plate. This method of construction is very economical and results in a reliable and standardized construction capable of connection in many ways to constitute various circuit requirements.

In Fig. 1 and Fig. 2 I have indicated an outlet box 30 to which the wall plate 10 is secured by a number of screws 31 in the customary manner, the wall plate being provided with a number of slots such as 32 to permit the attachment of the plate to different sizes and shapes of outlet boxes and also to permit angular adjustment of the wall plate for purposes of alignment.

It will be understood that the parts thus far described will be ordinarily installed in a building during the process of construction and the wiring completed, thus leaving the wire ends and the terminal plates and plug in contact sockets exposed. To temporarily protect the parts during completion of the construction and until the other parts of the telephone instrument are ready for installation, I provide a protector member 35 which is in the form of a steel case having lugs 36 adapted to be passed through the opening 23 and interlocked behind the upper edge 37. The lower edge of the case 35 is provided with a spring tongue 38 adapted to pass through the slot 39 in the wall plate so as to provide a frictional latching engagement.

The case 35 is large enough to cover the entire insulating block 11 and all terminals and contacts carried by it and also to cover the large conductor opening 23. It may also

have a flange or flanges such as 40 to extend outward far enough to cover some of the slots such as 41 which have been provided for the attaching screws. The principal protection required, however, is for the contact jaws, the terminal connections and the opening through which the conductors extend.

Instead of connecting the protector directly to the wall plate 10, I may employ one or more plates such as 43 secured to the case and adapted to be inserted into corresponding contact jaw sockets as shown in Fig. 4. Instead of using a number of small plugs in plates 43 as shown in Fig. 5, I may employ a single strip 44 as shown in Fig. 6, which is adapted to engage in a number of the contact sockets to provide the necessary frictional engagement to support the protector in this covering position.

20 I claim:

1. A telephone wall plate with circuit terminals and plug-in contacts and a detachable protector cover having means for securing it to the wall plate.

25 2. A telephone support comprising a wall plate having an opening for conductors, an insulating block mounted in the front of the plate and having terminals and connected contact jaws and a protector for the conductor terminals and jaws having means for detachably securing it to said support on said opening.

30 3. A terminal support for telephones comprising a wall plate, an insulating block having a passage through it with a groove in the rear, a contact jaw extending through said passage and having a foot in said groove, a terminal plate on the front of the block adjacent said jaw, a rivet securing the plate and foot to the block, a binding screw adjustable in said plate and means for securing said block on said wall plate.

35 4. A telephone installation comprising a wall plate having openings and a series of terminal plates and contacts and a protector casing for enclosing the plates and contacts and having fingers adapted to pass through the openings to hold the casing in place.

40 5. A telephone installation comprising a wall plate having a conductor opening and a series of terminal plates and contacts adjacent thereto, a protector casing and means for detachably securing the protector casing in place, covering said conductor opening and 45 the terminal plates and contacts.

JOSEPH O. CADIEUX.
